UNITED STATES PATENT OFFICE.

CHARLES H. STOKES, OF BALTIMORE, MARYLAND, ASSIGNOR OF ONE-HALF
TO GEORGE W. LOWDEN, OF SAME PLACE.

GUARD FOR CIRCULAR-SAW MILLS.

SPECIFICATION forming part of Letters Patent No. 417,204, dated December 10, 1889.

Application filed June 10, 1889. Serial No. 313,691. (No model.)

To all whom it may concern:

Be it known that I, CHARLES H. STOKES, a citizen of the United States, residing at Baltimore, in the State of Maryland, have invented certain new and useful Improvements in Guards for Circular-Saw Mills, of which the following is a specification.

This invention relates to a guard or safety device for circular saws. It is for use in ripping broad boards into narrow ones for flooring, ceiling, or wainscoting, and is designed to protect the operator who is feeding the boards to the saw.

Two saws are usually worked in ripping flooring to make three narrow boards, and it sometimes happens that as the narrow boards are about to pass from the saws one of the latter will catch a tooth into the end of a board, and throw it back with great force in the direction from whence it was fed, and in this way the person who is feeding the broad board is subjected to peril.

The object, therefore, of this invention is to prevent the boards from being thrown back, and thus protect the operator.

Figure 1 is a side view of a sawing-machine with my improved guard. Fig. 2 is a top view. Fig. 3 is a detail showing the guard.

The frame A, saw-shaft b, circular saws c, rollers d, and feed-rolls e are all of the usual construction.

My invention does not in any way change the construction of a sawing-machine.

The guard consists of a stop-board F, having at each end a journal or pivot g, which rest in suitable boxes or bearings h, secured to the frame A of the machine. The pivoted stop-board has position directly in front of the circular saws c. This stop-board is weighted at its lower edge i, and thereby the upper edge k is kept in an upwardly-projecting position, as shown. Suitable blocks l are se-

cured to the frame, and the stop-board comes against said blocks when in the upwardly-projecting position.

In the present instance the person who feeds the broad board stands at the left-hand end of the machine, and the boards move over the rollers d in the direction of the arrow toward the saws and pass over the stop-board F, causing the latter to tilt, the upper edge k tilting forward and down. The feed-rolls e will draw the board along while the saws cut it, and the moment the rear end of said broad board passes off the down-tilted stop-board the edge k of the latter will again project upward, and thus assume a position to stop the narrow boards and prevent them from being thrown back should the saws catch them, as above explained. Thus the pivoted stop-board F is no hinderance to feeding the boards to the saws, but will prevent the saws throwing a board back.

Having described my invention, I claim—

1. In a circular-saw machine, the combination of the frame, the circular saw, and a stop-board pivoted to the frame in front of the saws and weighted, substantially as described, whereby the stop-board will tilt down to allow the lumber to move toward the saw, and the moment the lumber has passed the stop-board the latter will tilt upward and prevent the lumber from being thrown back.

2. The combination of circular saws, a stop-board pivoted to the frame in front of the saws, and blocks l, against which the stop-board comes when in the upwardly-projecting position.

In testimony whereof I affix my signature in the presence of two witnesses.

CHARLES H. STOKES.
